APPARATUS FOR PRESSING CONDENSERS

Filed June 12, 1925

Fig. 2.

UNITED STATES PATENT OFFICE

CHESTER ARTHUR PURDY, OF OAK PARK, ILLINOIS, ASSIGNOR TO WESTERN ELECTRIC COMPANY, INCORPORATED, OF NEW YORK, N. Y., A CORPORATION OF NEW YORK

APPARATUS FOR PRESSING CONDENSERS

Application filed June 12, 1925. Serial No. 36,766.

This invention relates to an apparatus for producing electrical condensers.

The well known paper-foil type of electrical condenser is produced by winding a plurality of layers of paper and foil about a pair of metal strips which serve as terminals. The wound condensers are dried and then impregnated with melted paraffin, and afterwards pressed while the paraffin is solidifying. Since the closeness of the adjacent layers of foil and paper largely determines the electrical capacity which the completed condensers will possess, it is desirable that the condensers be subjected uniformly to a definite desirable pressure. In the past, condensers have been pressed by laying a plurality of them in a flat position upon a comparatively thick metal plate, covering them with another plate and then repeating the operation until a comparatively high stack was formed, after which a weight was placed on top of the stack to supply the requisite pressure to the condensers.

Objects of the present invention are to provide an improved apparatus for producing electrical condensers having substantially uniform electrical capacities.

In accordance with the general features of the present invention there is provided a plurality of press units having pivotally mounted ends connected by parallel rods, spaced in pairs and arranged to receive therebetween trays having apertured ends connected by angle members and strips constituting the bottom and side walls thereof, the upper angle members having portions extending outwardly to rest upon the upper rods of the press units when the trays are disposed therein. Disposed in the trays adjacent the ends thereof are plates between which are disposed horizontal rows of condensers separated by resilient members, the plates in the forward ends of the trays being engaged by rotatable ends of pistons moved inwardly by hydraulic force and arranged to allow the press units and the trays to be moved relatively thereto to move the condensers into horizontal positions while being pressed. The pistons are operated from a common source, thus insuring the application of the same hydraulic

pressure upon the condensers in each press unit.

A feature of the invention is the provision of means whereby the condensers treated with an impregnating material may be supported in horizontal position and pressed while in this position, allowing the impregnating material forced from the condensers, to drain therefrom.

The invention will be more fully understood from the following description and the accompanying drawings, wherein

Fig. 1 is a front elevational view of the apparatus, an intermediate portion of the view being broken away to conserve space;

Fig. 2 is a plan view of the apparatus shown in Fig. 1, an intermediate portion thereof being also broken away;

Fig. 3 is a fragmentary sectional view taken on the line 3-3 of Fig. 2;

Fig. 4 is an irregular sectional view taken on the line 4-4 of Fig. 3;

Fig. 5 is an enlarged fragmentary plan view showing the manner in which the condensers are placed in the trays;

Fig. 6 is an enlarged end elevational view of a press unit showing the manner in which it may be rotated through a 90° angle, and

Fig. 7 illustrates a type of condenser to manufacture which the invention is particularly adapted.

Referring now to the accompanying drawing, a framework 10 is provided upon which the remainder of the apparatus is mounted (Figs. 1, 2 and 3). A plurality of press units generally designated by the numeral 11 mounted upon the framework 10 may be supplied with suitable liquid under pressure through interconnected pipes 12 by a pump 13 of any suitable type. A reservoir 14 contains a reserve supply of the liquid, such as oil, which is employed to obtain the pressure in the pipe 12, a gauge 15 indicating the pressure therein, and a valve 16 being operable to release the pressure within the pipe 12 when desired.

The pipes 12 lead to each of the individual units, a valve 20 being so placed with respect to the unit as to regulate the admission of liquid thereto. Each valve 20 connects the

100

5 pipes with a cylinder 21 which has a flanged portion 22, said cylinder being suitably secured to the framework 10 by means of journal member 25. A ball bearing 26 is positioned between the flanged portion 22 of the cylinder 21 and a flanged member 27, which flanged member supports one end of a plurality of rods 30 leading to an end plate 31 to which the opposite ends thereof are secured by nuts 34. The end plate 31 has integral therewith a trunnion 32 which is journaled in a trunnion bearing 33 suitably secured to the main frame 10. A piston 35 is positioned in the cylinder 21 and is provided with suitable packing 36 to prevent leakage therearound. A piston rod 38 secured to the piston 35 has at its head end a flange 40 and has a central bore therein parallel to its axis, in which bore one portion of a bearing member 41 is placed. A cup-shaped member 42 contains a ball bearing 43, against which the bearing member 41 is placed. The flange 40 together with the cup-shaped member 42, bearing 43, and bearing member 41 are assembled as shown in section in Fig. 3 to form a piston head which, due to the ball bearing, can be rotated about the axis of the piston while the piston rod is held in a stationary position with respect to its axis. A member 45 is secured to the flanged member 27 to act as a housing for the piston head when the piston is in an unactuated or retracted position.

35 A tray provided for holding the condensers and adapted to be placed in the press unit comprises a pair of apertured end plates 51 and 52, a plurality of angle irons 53, and a plurality of flat strips 54, the open end plates, angle irons and flat strips being preferably 40 welded together to form an integral box-like structure with outwardly turned top angle irons 53 for engaging the top rods 30. Slidable plates 60 and 61 are placed within the tray at the ends thereof.

45 When producing condensers 50 in accordance with this invention, they are wound in the usual manner and placed by the operator immediately within the tray, with their ends resting upon and individually supported by 50 the bottom members 53 and 54, pairs of flexible separating plates 62, preferably of resilient metal, having outwardly curved edges 63 being placed between successive groups thereof (Figs. 4 and 5). The completely 55 filled tray is placed in a drying oven to remove whatever moisture may be present in the condensers, is then placed in a bath of heated paraffin to impregnate the condensers, and thereafter positioned within one of the 60 press units 11 (Figs. 2 and 3). After all of the units 11 have been filled, the pump 13 is actuated to produce a predetermined fluid pressure within the pipe 12. The valves associated with the units are opened so that 65 equal pressure is exerted upon the pistons 35

of all of the press units 11, thereby placing all of the condensers 50 under substantially uniform pressure. The pressure is transmitted between the groups through the separating plates 62, which due to their flexibility 70 permits the pressure on one condenser to be transmitted individually to the condenser in alignment therewith in the adjacent group without affecting or being affected by the pressures being transmitted by the other condensers in the same group. The pressure is maintained until the paraffin has solidified, the tray being turned in the manner indicated in dotted lines in Fig. 6 to facilitate 75 cooling and to prevent excessive amounts of 80 paraffin from flowing from between the layers of paper. This rotation of the tray about the axis of the piston is facilitated by the ball bearing associated with the head which permits the head to rotate with the 85 tray. Suitable means, such as electric fans (not shown) may be employed for the purpose of accelerating the rate of cooling and resulting rate of solidification of the paraffin. Since the condensers are supported endwise 90 upon the separated members 53 and 54, the melted paraffin readily drains therefrom by gravity.

When the condensers have cooled and the paraffin has solidified, the pressure is relieved 95 and the pistons 35 returned to their normal positions and the trays are then removed from the press units. The solidification of the paraffin binds the condenser together in each tray, but they may be readily separated without injury by inserting a suitable tool between the curved edges 63 of the metal separators to separate the adjacent groups. The metal separators 62 being substantially non-adherent the condensers may be readily removed from the associated groups, after which the individual condensers of the groups may be easily and safely separated from each other. The smooth surfaces of the metal separators also produce a glazed coating of paraffin on the surface of each condenser which serves as a protection therefor during subsequent handling.

Since the condensers are individually supported in continuous horizontal rows or trains, and the unit presses are each subjected to the same fluid pressure, the separators being uniformly flexible, all condensers are subjected to equal and uniform pressures throughout the pressing and solidification thereof. Thus due to the uniformity of the conditions imposed upon the condensers during the compressing thereof practically uniform electrical capacities are obtained. Furthermore, condensers may be pressed and solidified very quickly by the use of this apparatus, it being found that one hour is generally sufficient time in which to accomplish the entire pressing operation.

The invention is not to be limited to the 130

particular embodiment of the invention which has been described, but is only to be limited by the scope of the appended claims.

What is claimed is:

5 1. In apparatus for pressing condensers, a removable tray comprising open ends and sides for supporting a plurality of longitudinal columns of condensers, transverse flexible members separating the condensers, 10 each of said members having their opposite edges flared, and means for applying a pressure to the ends of the columns to press the condensers.

15 2. In apparatus for pressing condensers, means for supporting a plurality of condensers arranged in a horizontal row, means for applying pressure to the supported condensers in a horizontal direction, and means for permitting a rotation of the row of condensers on the horizontal axis thereof while the pressure is maintained.

20 3. In apparatus for pressing condensers, a framework, a tray for containing a plurality of condensers separated by flexible means, said tray having an apertured end and a plate member therein for closing the aperture, means attached to the framework for supporting the tray with the condensers in a horizontal row therein, a hydraulic press 25 having a cylinder rotatably mounted on the framework, a piston mounted within the cylinder, a rotatable head carried by the piston and adapted to enter the aperture in the end of the tray and engage the plate 30 member within the tray, and means for operating the press to cause the condensers and flexible separating means within the tray to be pressed between the plate member and the opposite end of the tray.

35 4. In an apparatus for pressing condensers, a plurality of rods arranged in parallelism, a tray comprising side members with outwardly extending flanges engaging said rods, and a plurality of narrow strips 40 constituting the bottom thereof, each of said strips supporting a column of electrostatic condensers, and means operated centrally with respect to said rods for uniformly compressing the condensers contained in said 45 tray.

50 5. In an apparatus for pressing condensers, a plurality of rods arranged in parallelism, a tray comprising side members with outwardly extending projections engaging said rods and a plurality of narrow strips constituting the bottom thereof, each 55 of said strips supporting a column of electrostatic condensers, and end members having apertures, and means extending through the 60 apertures in one of the end members for compressing the condensers contained in the tray.

55 6. In an apparatus for pressing condensers, a removable tray for supporting a plurality of condensers, means for applying

pressure to the condensers supported in said tray, and means for permitting a rotation of the tray on the horizontal axis thereof while the pressure is maintained.

In witness whereof, I hereunto subscribe 70 my name this 1st day of June, A. D. 1925.

CHESTER ARTHUR PURDY.
